UNITED STATES PATENT OFFICE.

LOUIS JAENICHEN, OF DETROIT, MICHIGAN, ASSIGNOR TO THE STANDARD COMPUTING SCALE COMPANY, OF DETROIT, MICHIGAN, A CORPORATION OF MICHIGAN.

DESIGN FOR A SCALE-FRAME.

50,688.

Specification for Design.

Patented May 1, 1917.

Application filed November 15, 1915. Serial No. 61,698. Term of patent 14 years.

To all whom it may concern:

Be it known that I, LOUIS JAENICHEN, a citizen of the United States, residing at Detroit, in the county of Wayne and State of Michigan, have invented a new, original, and ornamental Design for Scale-Frames, of which the following is a specification, ref-

erence being had to the accompanying drawing, forming part thereof, which is a perspective view of the scale frames.

I claim:

The ornamental design for a scale frame, as shown.

LOUIS JAENICHEN.
